UNITED STATES PATENT OFFICE.

GEORGE P. FENNER, OF NEW LONDON, CONNECTICUT.

INKING ARRANGEMENT FOR PRINTING-PRESSES.

No. 872,805.

Specification of Letters Patent.

Patented Dec. 3, 1907.

Application filed August 16, 1907. Serial No. 388,899.

To all whom it may concern:

Be it known that I, GEORGE P. FENNER, a citizen of the United States, residing at New London, in the county of New London and 5 State of Connecticut, have invented new and useful Improvements in Inking Arrangements for Printing-Presses, of which the following is a specification.

This invention relates to means by which 10 the vibration of ink rollers can be regulated or entirely stopped.

This invention is set forth in the following specification and claim and illustrated in the annexed drawing, in which—

15 Figure 1 is the side elevation of an inking arrangement embodying this invention. Fig. 2 is a plan view of Fig 1. Fig. 3 is an end view of Fig. 1.

In this drawing is shown a gear *a* for rotating the ink rollers and a fork *b* engaging a spool *c* and actuated by a nut *d* to vibrate the ink roller. There are two nuts *d* shown in the drawing but the explanation of one also explains the other.

20 Each nut *d* is connected by a link *e* to a casting or lever piece *r* having a fulcrum or pivot on a bracket or arm *f*. The nut *d* by link *e* engages and vibrates the lever piece *r* and by pivot *g* and link *h* this vibration is 25 conveyed to fork *b* and spool *c* and thence to ink roller *k*. The rack *m* rotating gear *a* also imparts the required rotation to screw *p* actuating the nut *d*. The spool *c* as also gear *o* are on the shaft of the vibrating roller *k*.

30 In Fig. 2 at the left the pivot connection *g* is shown at a distance from the fulcrum point of lever *r*, on bracket *f*, while at the right the pivot *g* is shown set over or to coincide or register with the pivot or fulcrum 35 point of the lever *r*. As the connection *h* or its pivot *g* is set to one extreme or another the vibration of the roller *k* can be varied from a considerable extent down to nothing or entirely eliminated. The levers *r* are 40 shown independent of one another and at each

lever the adjustment can be made for a respective vibration of roller as desired.

I do not claim anything set forth in U. S. Patent 818,238, granted April 17, 1906, for inking arrangement for printing presses. 50

The reason for stopping this vibration altogether is: because there is, sometimes, more than one color of ink in the ink fountain. This fountain has partitions, in which case, the endwise motion of the vibration of 55 the steel rollers would tend to work these different colors of ink altogether. If the vibration is stopped, this tendency is cured.

Now what I claim is:

1. A device for regulating the vibration of 60 an ink roller which comprises a vibrator nut or screw, a lever piece vibrated by the nut and a link for conveying motion from the lever piece to the roller, said link being adjustable to coincide with the fulcrum of the 65 lever to eliminate vibration.

2. A device for regulating the vibration of 70 an ink roller which comprises a vibrator nut or screw, a slotted lever actuated by the nut, and a link for connecting the lever and roller, 70 said link having its connection adjustable along the slot of the lever to coincide with or be out of register with the fulcrum.

3. A device for regulating the vibration of 75 an ink roller which comprises a vibrator nut or screw, a lever piece vibrated by the nut, a fixed bracket, a fulcrum for the lever supported on the bracket, and a link for conveying motion from the lever piece to the roller, said link being adjustable to coincide 80 with the fulcrum of the lever to eliminate vibration.

In testimony whereof I have hereunto set my hand in the presence of two subscribing witnesses.

GEO. P. FENNER.

Witnesses:

ANNA O. RASMUSSEN,
EVA LOUISE HUDSON.
